MICROWAVE DEVICE

Irving Wolff, Merchantville, N. J., assignor to
 Radio Corporation of America, a corporation of
 Delaware

Application July 21, 1939, Serial No. 285,730

17 Claims. (Cl. 250—27)

This invention relates to microwave devices and more especially to a centimeter wave thermionic tube of the velocity modulation type.

Thermionic tubes, designed for ultra high frequency oscillations, have been arranged so that the electrons of a stream or beam of electrons are grouped in fast and slow moving electronic clouds. Such grouping as a function of velocity is brought about by the suitable application of electric fields and is known as velocity modulation.

The present invention has for one of its objects the provision of improved means for velocity modulating a stream of electrons. Another object is to provide an efficient velocity modulation tube. Another object is to provide a microwave tube of the velocity modulation type occupying a smaller volume than heretofore considered practical. An additional object is to provide means for applying multiple velocity modulation to a stream of electrons.

The invention will be described by reference to the accompanying drawing which represents in a perspective view one embodiment of the invention. A source of electrons 1, truncated conical controlling electrodes 3, 5 and a cylindrical electrode 7 are arranged within one end of an evacuated envelope 9 which preferably includes a conductive film 10. A first half wave split anode electrode 11 is mounted within the envelope adjacent the cylindrical electrode and in axial alignment therewith. A second half wave split anode electrode 13 is mounted within the envelope coaxially with and spaced from the first mentioned half wave electrode. Transmission lines 15, 17 are connected respectively to the first and second half wave electrodes and are terminated respectively in an input circuit 19 and an output circuit 21, represented by way of example as antennas. The ends of each of the two half wave split anode electrodes are connected respectively by short circuiting rings 23.

A hollow conical collecting electrode 25 is disposed between the adjacent ends of the half wave electrodes 11, 13. A second collecting electrode 27, composed of a plurality of triangular shape radially mounted vanes 29, is mounted adjacent the end of the second half wave split anode electrode. The cylindrical electrode 7, and split anode electrodes 11, 13 are biased positively with respect to the electron source 1. The controlling electrodes 3, 5 and the collecting electrodes 25, 27 are also biased positively.

The envelope is surrounded by a solenoid 30, which is shown in section to avoid complicating 55

the drawing. Auxiliary solenoids 31, also shown in section, are arranged near the electron gun to increase the magnetic field near that point. The solenoids are energized by appropriate power sources 33. It should be understood that the magnetic fields may be established by permanent magnets or other suitable means.

The operation of the device is as follows: Electrons emitted from the source would, in the absence of a magnetic field, travel along straight lines, and, being emitted from a plurality of points, would not be beamed narrowly but would be spread over a considerable area. Under the influence of the magnetic and electric fields, the electrons spiral outwardly, and at the same time the increased magnetic field and the distribution of the electric field near the electron source, followed by the decreased magnetic field and increased electric field, cause the electrons to form, first, a hollow rotating and advancing cylinder of increasing diameter, and, second, a rotating hollow cylinder. The cylinder advances continuously from the gun toward the final collecting electrode 27.

If the magnetic field is so adjusted that the rotation period of the electrons within the split anode electrode 11 and 13 is the same as the period of the currents applied to the input transmission line 15, electrons will pass the slit between the anode electrodes in the same phase. If desired, more slits can be used, in which case the period of the applied current would be a higher multiple of the rotation period. Therefore, certain electrons will be decelerated while others will be accelerated. The accelerated electrons will have the radius of their paths increased; the decelerated electrons will have the radius of their paths decreased. The decelerated electrons, moving in smaller circles, will be collected by the conical electrode 25, which is preferably designed to dissipate the heat developed by the electron impact.

After the removal of the slower electrons, a rotating cylinder of electrons of variable charge density remains. This generates an amplified voltage on the second split anode electrode 13. The amplified voltage is transferred by the transmission line 17 to the output circuit 21. The electrons passing through the second or output split anode electrode strike the flanges of the final collecting electrode 27. The flanges, duly polarized and being radially arranged and being of triangular shape, influence the electron paths so that the electrons getting within the influence of one flange will be likely to hit the next one.

Any secondary electrons emitted by the impact will be trapped within the flanges. The final collecting electrode is made preferably of a material which will radiate the heat generated by electron impact without liberating gases.

Thus the invention has been described as a microwave amplifier of the velocity modulation type. The electrons rotate within split anode electrodes to form therein hollow cylinders of electrons. The electrons advance toward collecting electrodes. In the first split anode electrode the electrons are grouped or modulated to form a variable charge density and the slower electrons are collected. The thus modulated electrons generate amplified voltages in the second split anode electrode. The electrons are collected by a final electrode. The number of modulations within the split anode electrode depends upon the rate at which the electrons advance toward the final electrode. A multiple number of modulations may be readily and efficiently obtained within a small space.

The number of rotations the electrons make inside the split electrode must be adjusted, having several factors in mind: The greater the number of rotations, the greater the sensitivity. However, the width of the pass band of the system becomes less. Also, a tendency towards regeneration becomes greater since the electrons with reduced orbit diameters have less effect on the electrodes and, to a certain extent, charge density effects are obtained even before the slower moving electrons are removed. If the input 19 and the output 21 are coupled, feedback, in appropriate phase, will cause continuous oscillations to be generated.

I claim as my invention:

1. A microwave device including in combination a source of electrons, controlling electrodes, a first and a second split anode electrode, means for forming electrons emitted from said source into an advancing rotating substantially hollow cylinder of electrons, means for directing said cylinder of electrons through said split anode electrodes, means for applying alternating currents to one of said split anode electrodes, means for adjusting the rotational rate of said electrons within one of said split anode electrodes to correspond to the period of said alternating currents so that certain electrons are accelerated and others decelerated and thereby arranged in rotating variable charge density groups, means for directing the accelerated electrons of said variable charge density electrons groups through the other of said split anode electrodes so that voltages are generated therein, and means for utilizing said voltages.

2. In a device of the character of claim 1, means for collecting said decelerated electrons.

3. In a device of the character of claim 1, means for collecting the electrons passing through said last mentioned split anode electrode.

4. In a device of the character of claim 1, means for collecting said decelerated electrons, and means for collecting the electrons passing through said last mentioned split anode electrode.

5. A microwave device including in combination a source of electrons, electron controlling electrodes, a pair of half wave split anode electrodes coaxially arranged with respect to said source and in spaced relation, means for forming electrons emitted from said gun into an advancing rotating substantially hollow cylinder of

electrons, means for directing said cylinder of electrons through said split anode electrodes, an input circuit, means for impressing alternating currents applied to said input circuit upon the first of said split anode electrodes, means for adjusting the rotational period of said cylinder of electrons to correspond to the period of said alternating currents so that certain of the electrons of said cylinder are accelerated and others decelerated, means for collecting the decelerated electrons whereby the remaining electrons form variable charge density groups in the rotating cylinder, means for passing the variable charge density electron groups through said second split anode electrode to generate voltages therein, an output circuit for utilizing said voltages, and a collecting electrode for collecting electrons passing through said second split anode electrode.

6. In a device of the character described, an evacuated envelope including a source of electrons, means for establishing a magnetic field, means for establishing an electric field, means for adjusting at least one of said fields so that the electrons from said source form a substantially hollow rotating electronic cylinder of increasing diameter, and means for converting said cylinder of increasing diameter into a cylinder of substantially constant diameter.

7. In a device of the character described, an evacuated envelope including a source of electrons, means for establishing a non-uniform magnetic field, means for establishing an electric field, means for adjusting at least one of said fields so that the electrons from said source form a substantially hollow rotating and advancing electronic cylinder of increasing diameter, and means for converting said cylinder of increasing diameter into a cylinder of substantially constant diameter.

8. In a device of the character described, an evacuated envelope including a source of electrons, means for establishing an electric field, means for establishing a magnetic field of increasing strength adjacent said source, means for adjusting at least one of said fields so that the electrons from said source form a substantially hollow rotating electronic cylinder of increasing diameter, and means for converting said cylinder of increasing diameter into a cylinder of substantially constant diameter.

9. In a device of the character described, an evacuated envelope including a source of electrons, means for establishing a magnetic field, hollow truncated conical electrodes for establishing electric fields, said magnetic and electric fields being arranged to form the electrons emitted from said source into a rotating substantially hollow cylinder of increasing diameter, and means for converting said cylinder of increasing diameter into a cylinder of substantially constant diameter.

10. In a device of the character described, means for establishing a substantially hollow rotating and advancing electronic cylinder, and a collecting electrode for said electrons, said electrode including a plurality of vanes arranged along the line of said advancing electrons and increasing in width along said line.

11. In a device of the character described, means for establishing a substantially hollow rotating and advancing electronic cylinder, and a collecting electrode for said electrons, said electrode including a plurality of vanes arranged in intersecting planes and having increasing area along the line of said advancing electrons whereby secondary electrons emitted by the collection

of said advancing electrons are collected by said vanes.

12. High frequency apparatus including means for producing a stream of orbitally moving electrons in which the center of orbital motion progresses along a given axis, a pair of spaced conducting members defining an elongated gap which extends generally parallel to said axis in proximity to the electron stream, the said gap being of sufficient length so that individual electrons are caused to pass the gap a plurality of times, means for impressing a high frequency voltage between the said conducting members, thereby to produce variations in the orbital velocity of the various electrons as a result of the potential gradients developed across the said gap, and energy-abstracting means positioned to be affected by variations existing in the electron stream at a point which is axially displaced from the said gap.

13. High frequency apparatus including means for producing a stream of orbitally moving electrons in which the center of orbital motion progresses along a given axis, a pair of semi-cylindrical conductive parts which are juxtaposed to define a cylindrical chamber arranged for traversal by the electron stream, the said parts being mutually spaced to provide axially extending gaps between their juxtaposed edges, means for impressing a high frequency voltage between the semi-cylindrical parts so as to vary the orbital velocity of the various electrons in accordance with the potential gradients thus developed across the said gaps, a second pair of semi-cylindrical conducting parts axially displaced from the first pair and arranged to define a second hollow chamber which is traversed by the electron stream after its traversal of the first chamber, said second pair of parts being also mutually spaced to provide axially extending gaps between their juxtaposed edges, said gaps being generally parallel to the first mentioned gaps, and circuit means connected between the second pair of parts so as to be excited thereby in accordance with variations existing in the electron stream upon its traversal of the said second chamber.

14. High frequency apparatus including a source of electrons, means defining a chamber traversed by electrons emitted from said source, spaced conductive members adjacent the path of the electrons and providing between them a narrow gap which extends longitudinally of the chamber, means connecting with the said conductive members for impressing between them a cyclically varying voltage of predetermined frequency, means including a source of magnetic flux for causing the electrons traversing the chamber to follow a generally helical path of such character that the individual electrons are brought several times into proximity with said gap before passing beyond its extremity, the average orbital transit time of the electrons being appropriate to assure that the electron velocity variations produced at the said gap are cumulative for each successive electron passage, and energy-

abstracting means adapted to be affected by the variations existing in the stream at a region which is displaced from the said first-named region in a direction along the axis of the electron path.

15. High frequency apparatus including means for producing a stream of orbitally moving electrons in which the center of orbital motion progresses along a given axis, a pair of spaced conducting members defining an elongated gap which extends generally parallel to said axis in proximity to the electron stream, the said gap being of sufficient length so that individual electrons are caused to pass the gap a plurality of times, means for impressing a high frequency voltage between the said conducting members thereby to produce variations in the orbital velocity of the various electrons as a result of the potential gradients developed across the said gap, additional spaced conducting members defining a second elongated gap extending generally parallel to the first gap in a region which is axially displaced therefrom, and circuit means connected with the said additional conducting members and adapted to be excited thereby in accordance with variations existing in the electron stream upon its traversal of the said second gap.

16. High frequency apparatus including means for producing a stream of orbitally moving electrons in which the center of orbital motion progresses along a given axis, spaced conducting members defining a pair of circumferentially displaced parallel gaps which extend substantially parallel to the axis of the electron stream in close proximity to the stream, each gap being of sufficient length so that individual electrons are caused to pass the gap a plurality of times, common means for producing cyclically varying potential gradients across the said gaps so as to cause recurrent variations in the orbital velocity of the electrons which traverse the gaps, the spacing of the gaps being so correlated to the average velocity of the electrons as to assure the occurrence of cumulative effects at the two gaps, and energy-abstracting means positioned to be affected by variations existing in the electron stream at a region which is axially displaced from the said gaps.

17. High frequency apparatus including means for producing a stream of orbitally moving electrons in which the center of orbital motion progresses along a given axis, a pair of semi-cylindrical conductive parts which are juxtaposed to define a cylindrical chamber arranged for traversal by the electron stream, the said parts being mutually spaced to provide axially extending gaps between their juxtaposed edges, means for impressing a high frequency voltage between the semi-cylindrical parts so as to vary the orbital velocity of the various electrons in accordance with the potential gradients thus developed across the said gaps, and energy-abstracting means arranged to be affected by the variations existing in the electron stream subsequent to its traversal of the said chamber.

IRVING WOLFF.
